UNITED STATES PATENT OFFICE.

WALTER ALLAN PORTEOUS, OF PHILADELPHIA, PENNSYLVANIA.

DESIGN FOR A SUPPORTING STAND.

Application filed March 22, 1929. Serial No. 30,589. Term of patent 14 years.

To all whom it may concern:

Be it known that I, WALTER A. PORTEOUS, a subject of the King of Great Britain, and a resident of the city of Philadelphia, in the county of Philadelphia and State of Pennsylvania, whose post-office address is 1411 Walnut Street, Philadelphia, Pennsylvania, have invented a new original, and ornamental Design for a Supporting Stand, of which the following is a specification, reference being had to the accompanying drawing, forming a part thereof.

I claim:

The ornamental design for a supporting stand substantially as shown.

WALTER ALLAN PORTEOUS.
